UNITED STATES PATENT OFFICE.

JOHN R. MILSON, OF WATERTOWN, MASSACHUSETTS, ASSIGNOR, BY MESNE ASSIGNMENTS,
TO LISTER-NOBLE ROLLER COMPANY, A CORPORATION OF MASSACHUSETTS.

DRAWING-OFF ROLL.

No. 911,317.

Specification of Letters Patent.

Patented Feb. 2, 1909.

Application filed November 29, 1907. Serial No. 404,429.

To all whom it may concern:

Be it known that I, JOHN R. MILSON, a citizen of the United States, residing at Watertown, in the county of Middlesex and State 5 of Massachusetts, have invented certain new and useful Improvements in Drawing - Off Rolls, of which the following is a specification, reference being had therein to the accompanying drawing.

10 This invention relates to drawing-off rolls for wool combs gill-boxes, and the like and the object of the invention is to provide a pair of rolls that can be used without a leather apron to engage and draw off the 15 wool fringe from the comb teeth without injuring the fiber, and pass the same in the form of a sliver through the trumpet to the coiler, or balling head.

It is found in practice that fluted drawing- 20 off rolls always cut the wool unless they have a leather or some yielding material between them to act as a cushion against which the wool is nipped. These leathers have heretofore been made in the form of endless aprons 25 which, owing to the severe bending strains to which they are subjected in passing through the corrugated rollers, soon wear out. Then again, the wear caused by the action of drawing the fibers from the comb through the pins 30 also assists in destroying the apron, usually by wearing away the middle portion of the same. These aprons are usually of the very best quality of leather and are consequently very expensive, and as several of said aprons 35 are employed in each of the combing machines the expense of constantly replacing them to maintain the efficiency of the machine, is considerable.

By the use of my improved device a pair of 40 especially constructed corrugated rolls are provided which effectually does away with these leather aprons. These rolls are provided with teeth having pins so arranged as to engage the wool, draw it from the comb 45 and pass it through the rolls. The nipping line between the teeth is provided with a cushion or suitable flexible means to effectually prevent the cutting of the fibers as they are nipped therein.

50 Heretofore where the aprons were used the fluted rolls were obliged to be made of considerable size so as to prevent a too rapid cutting of said aprons, but by my improved construction the rolls may be made much smaller 55 allowing the nipping line of the rolls to be

brought much closer to the comb circles thereby drawing out more of the fibers, or saving more of the long stock, and leaving less waste or noils in the small circle.

Another feature of my improved rolls is 60 that the same are equally well adapted to be used as the front rollers in a gill-box, where they are of great advantage, first, by doing away with the leather apron ordinarily used there, and second, that by being so much 65 smaller the shorter fibers can reach the nip before the pins of the fallers are withdrawn from the sliver.

This invention consists of other novel features and parts and combinations of the 70 same as will be fully described hereinafter and then pointed out in the appended claims.

A practical embodiment of the invention is represented in the accompanying drawings, forming a part of this specification, in which 75 similar characters of reference indicate corresponding parts in all the views.

In the drawings: Figure 1—is a central sectional elevation of a comb showing my improved drawing-off rolls attached thereto. 80 Fig. 2—is a diagrammatic plan view of the comb circles showing my improved rolls as applied both to the larger circle and also to the smaller circle for drawing the fringe therefrom and passing the same through the 85 trumpet to the coiler. Fig. 3—shows the application of my improved rolls to a gill-box. Fig. 4—is a side elevation of the corrugated binding roll. Fig. 5—is a side elevation of the pin roll, the teeth of which 90 latter roll are formed by a thin blade having a row of pins on each side thereof, and the space between said teeth being provided with a cushioned surface. Fig. 6—is a central sectional side elevation of the pin roll. 95 Fig. 7—is a enlarged sectional end view of said pin roll. Fig. 8—is a sectional end view of the binding roll. Fig. 9—is a perspective view showing both of the rolls together and the bearing for supporting the 100 same. Fig. 10—is an end view of one of the bearings showing the adjustable spring tension on the boxes. Fig. 11—is a modification showing the pin roll as constructed with a row of short pins projecting from the 105 edge of each tooth and a leather nip cushion between said teeth. Fig. 12—shows a strip of leather at 33 on the outer edge of the teeth of the binding roll 7. Fig. 13—shows a modified construction wherein the pins 110

are removed from the drawing-off rolls and a cushioning means is provided for both of said rolls.

Referring to the drawings at 1 is the 5 frame of what is commonly known as the Noble combing machine, in which the large comb circle is represented at 2—2 and the two small comb circles on either side at 3—3.

The dabbing brushes, which strike the 10 stock down between the teeth of the comb, are illustrated at 4 and 5, and my improved drawing off rolls, which may be applied equally well to both the large and small circles, are represented at 6 and 7. These 15 drawing-off rolls are set on end and run in pairs. The pin roll 6, which sets nearest to the approaching fringe to engage and draw it into the rolls, is mounted on the shaft 14 and constructed as follows: The middle 20 portion of the roll is provided with a shell or hub 9, which may be keyed or otherwise secured to said shaft. Teeth are formed on this shell by blades 10—10 which radiate outward at intervals all around the outer 25 surface of said shell. These blades may be made separate and set into the shell or made integral with the shell, if desired. Projecting upward at close intervals all along on either side of these blades 10 are the two rows of 30 pins 11—11, their upper ends being pointed and extending to substantially the same height as the blades. At either end of the middle portion of this roll are the narrow corrugated driving gears 12 and 13, also 35 connected to said shaft 14. These gears are for the purpose of meshing with similar gears on the corresponding roll 7 to keep said rolls in time with each other. Outside of these gear are collars 15—15 also mounted 40 on said shaft, and encircling these collars 15—15 are the retaining rings 16—16. These collars and rings are for the purpose of receiving the ends of the spring or flexible 45 nip members 17 which are located between the blades 10—10 and are for the purpose of forming a cushion for receiving the pressure of the teeth of the binding roll to prevent the same from injuring the fibers of the wool as they are pulled or drawn from the 50 comb pins through the rolls. It will be seen that there is a space between the periphery of the collar and the inner circle of the ring whereby these spring or flexible nip members may slide when they yield and 55 are elongated by the nipping pressure. At 18 and 19 at either end of this roll are nuts adapted to be screwed up on the threaded portion 20 of the shaft to hold all the members of this roll and lock the same in position.

60 A second or binding roll 7 is mounted on the upright shaft 23 the ends of said roll being provided with narrow gears 24—24 which are adapted to mesh with the corresponding gears 12 and 13 on the opposite roll 6. These gears are held in position on

said shaft by means of the threaded collars 25 and 26. Both of these rolls receive their motion through the driving gear 27. The middle portion of this roll is provided with a corresponding number of outwardly projecting teeth 21 which mesh with the pin roll and force the fibers down between the blades onto the points of the pins and to bite or press the fibers against the nip members. I have shown the gears of both shafts as being 70 made separate from the rolls, but they may be made all in one piece if desired, or in any other convenient way, their function being simply to keep the rolls in time with each other.

The spaces between the teeth of the middle portion of this roll are cut deeper than the teeth on the opposite roll, and the sides of the teeth are also undercut or cut away at 22, all for the purpose of clearing the points of the pins as the rolls revolve. The fiber is drawn from the comb by means of these pins in combination with the bite of the teeth of the binding roll onto the flexible nip member, and said fiber is thus firmly held and prevented from slipping. Then again by this construction the fiber is readily released to be withdrawn from the roll at its delivery side without lapping around the same, as the blades 10 between the pins prevent the wool from being forced too deeply onto the pins, and the spring of the flexible cushion also has a tendency to raise the fiber from said pins.

I have shown a metal spring to serve as a 95 nip member, but leather, rubber, or any other suitable flexible material, which may serve as a cushion, may be used for this purpose if desired, and in some cases the pins may be omitted and the cushion nip be depended upon alone to draw the fiber from 100 the comb, and if desired the teeth of both rolls may be caused to cushion one upon the other, as shown in Fig. 13, to increase the drawing power of said rolls. Any amount of tension or pressure of one roll upon the 105 other may be obtained by setting up the screws 28 and 29 onto the spring 30 and bearing 31 in the frame 32, as illustrated in Fig. 10.

This construction of rolls is equally well adapted to be used as the front rolls 34 on 115 gill-boxes to do away with the usual apron from which the sliver is led to the boller, or the same may be used in silk, flax and jute machines, or any other fiber operating machinery in which the same may be adapted 120 to operate in a practical manner.

I do not restrict myself to placing the 125 cushions between the teeth of the pin roll, as cushion strips may be held on the outer edges of the teeth of the binding roll, if desired. Neither do I wish to be restricted to the arrangement of the pins 1 in the rows with a blade between them, as the roll may be constructed with the pins 35 on the edges of the teeth, as shown in Fig. 11, if desired, and in 130

fact in the operation of some fibers the pins may be done away with altogether depending entirely upon the flexible nip of the rolls for drawing off the fiber, and therefore any arrangement of rolls having a combination of both pins and cushions or cushions alone attached to the rolls to act upon the fiber would come within the spirit and scope of my invention.

10 My improved rolls are practical in their construction and effective in their operation and by their use combs and gill-boxes and analogous machines to which these rolls may be applied may be operated at much less expense, as the costly aprons are done away with and at the same time a greater percentage of the long fiber is saved.

Having thus described my invention, what I claim as new and desire to secure by Letters Patent, is:

1. In a machine of the character described, a pair of drawing-off rolls, cushioning means secured between the teeth of one of said rolls against which the fibers may be nipped without injuring the same.

2. In a machine of the character described, a pair of drawing-off rolls, cushioning means between the teeth of one of said rolls against which the fibers may be nipped by the teeth of the opposite roll without injuring the fiber, and means for securing said cushioning means to said roll.

3. In a machine of the character described, a pair of drawing-off rolls, cushioning means secured to one of said rolls against which the fibers may be nipped without injuring the same, and a plurality of pins arranged to act on the fiber to assist in drawing in the same.

4. In a machine of the character described, a drawing-off roll provided with teeth, and a plurality of pins adapted to work in conjunction with said teeth to engage the fiber to assist in drawing in the same.

5. In a machine of the character described, a drawing-off roll provided with teeth, and a row of pins on each side of the teeth adapted to work in conjunction with said teeth to engage the fiber to assist in drawing in the same.

50 6. A drawing-off roll for combs and gill-boxes provided with a plurality of rows of pins for engaging and drawing in the fiber, and means for limiting the depth to which said fiber can be drawn into said pins.

55 7. Drawing-off rolls for combs and gill-boxes comprising a pin roll provided with a plurality of rows of pins for engaging and drawing in the fiber, means for limiting the depth to which said fiber can be drawn into said pins, and a roll adapted to run in time with said pin roll to assist in drawing the fibers.

60 8. Drawing-off rolls for combs and gill-boxes comprising a pin roll provided with a plurality of pins for engaging and drawing in

the fiber, means for limiting the depth to which said fiber can be drawn into said pins, and a fluted roll adapted to mesh with said pin roll to assist in drawing the fibers.

9. Drawing-off rolls for combs and gill-boxes comprising a pin roll provided with a plurality of pins for engaging and drawing in the fiber, a fluted roll adapted to mesh with said pin roll to assist in drawing the fibers, and cushioning means against which the fibers may be nipped between the teeth of the pin roll.

10. Drawing-off rolls for combs and gill-boxes, comprising a pin roll provided with a plurality of pins for engaging and drawing in the fiber, means for limiting the depth to which said fiber can be drawn into said pins, a fluted roll adapted to mesh with said pin roll to assist in drawing the fibers, and cushioning means against which the fibers may be nipped between the teeth of the pin roll.

11. Drawing-off rolls for combs and gill-boxes, comprising a pin roll provided with a plurality of rows of pins for engaging and drawing in the fiber, a fluted roll adapted to mesh with said pin roll to assist in drawing the fibers, and cushioning means in said pin roll against which the teeth in the fluted roll may nip the fiber.

12. Drawing-off rolls for combs and gill-boxes, comprising a pin roll provided with a plurality of rows of pins for engaging and drawing in the fiber, means for limiting the depth to which said fiber can be drawn into said pins, a fluted roll adapted to mesh with said pin roll to assist in drawing the fibers, and cushioning means in said pin roll against which the teeth in the fluted roll may nip the fiber.

13. Drawing-off rolls for combs and gill-boxes, comprising a pin roll provided with a plurality of pins for engaging and drawing in the fiber, means for limiting the depth to which said fiber can be drawn into said pins, a fluted roll adapted to mesh with said pin roll to assist in drawing the fibers, a cushion between the teeth of said pin roll against which the teeth of the fluted roll may nip the fiber, and means for holding said cushions at either end of the pin roll.

14. In a device of the character described, a drawing-off roll for combs and gill-boxes provided with a plurality of rows of pins for engaging and drawing in the fiber, and a thin blade set between the rows for limiting the depth to which said fiber can be drawn into said pins.

15. In a device of the character described, a drawing-off roll for combs and gill boxes provided with a plurality of teeth, each tooth being constructed of a thin blade and a row of pins on either side of each blade to assist in drawing in the fiber.

16. In a device of the character described, a drawing-off roll for combs and gill-boxes

provided with a plurality of teeth each tooth being constructed of a thin blade, a row of pins on either side of each blade to assist in drawing in the fiber, and a fluted roll adapted to mesh with said pin roll to assist in drawing the fibers.

17. In a device of the character described, a drawing-off roll for combs and gill-boxes provided with a plurality of teeth, each tooth being constructed of a thin blade, a row of pins on either side of each blade to assist in drawing in the fiber, a fluted roll adapted to mesh with said pin roll to assist in drawing the fibers, and cushioning means against which the fibers may be nipped between the teeth of the pin roll.

18. In a device of the character described, a drawing-off roll for combs and gill-boxes provided with a plurality of teeth, each tooth being constructed of a thin blade, a row of pins on either side of each blade to assist in drawing in the fiber, a fluted roll adapted to mesh

with said pin roll, a cushion between the teeth of said pin roll against which the teeth of the fluted roll may nip the fiber, and means for holding said cushions at either end of the pin roll.

19. In a device of the character described, a drawing-off roll for combs and gill-boxes provided with a plurality of teeth, each tooth being constructed of a thin blade, a row of pins on either side of each blade to assist in drawing in the fiber, a fluted roll adapted to mesh with said pin roll, a nip cushion between the teeth of said pin roll, a collar for holding said cushions at either end of the pin roll, and means for driving said rolls in time with each other.

In testimony whereof I affix my signature in presence of two witnesses.

JOHN R. MILSON.
